UNITED STATES PATENT OFFICE.

OWEN ELSWORTH VANCE AND PAUL STANLEY BAKER, OF MUSCATINE, IOWA.

AUTOMATIC COOKER.

1,139,932.

Specification of Letters Patent.

Patented May 18, 1915.

Application filed December 2, 1914. Serial No. 875,155.

To all whom it may concern:

Be it known that we, OWEN E. VANCE and PAUL S. BAKER, citizens of the United States, residing at Muscatine, in the county of Muscatine and State of Iowa, have invented certain new and useful Improvements in Automatic Cookers; and we hereby declare that the following is a full, clear, and exact description thereof, reference being had to the accompanying drawings, which form part of this specification.

This invention is a novel improvement in automatic apparatus for cooking or heating packaged goods, particularly canned goods.

The object of the invention is to provide a machine having a heating chamber to which the cans can be fed continuously and from which they can be continuously delivered and wherein they may be retained a sufficient time in traveling from the feed to the delivery to insure the desired heating or cooking of the contents of the cans; and in which the cans can be subjected to jets of steam by which their contents can be heated to any desired temperature necessary for the cooking or preserving thereof. The machine will receive cans, agitate them while being treated, heat them uniformly and quickly, and discharge them safely. The cans can be fed to the machine continuously or intermittently, and the cans cannot jam therein as there is only one moving part inside of the machine by which the cans are conveyed from the feed to the discharge end.

We will explain the invention more in detail with reference to the embodiment thereof illustrated in the accompanying drawings, in which:—

Figure 1 is a side elevation of the complete machine. Fig. 2 is an end view thereof. Fig. 3 is an enlarged vertical section thereof on the line 3—3, Fig. 4. Fig. 4 is a transverse vertical section thereof. Fig. 5 is a detail horizontal sectional view of the discharge end of the machine. Fig. 6 is a detail of the driving mechanism on line 6—6, Fig. 2.

The machine preferably comprises a cylindric tank or chamber having an outer

wall 1 closed by heads 1^a and 1^b suitably secured thereto. Suitably journaled in the bars of the head 1^a is an axially disposed shaft 2 which extends outwardly through the bearing 1^c on head 1^a and may be provided with a suitable stuffing box or gland 2^a.

Upon the shaft 2 within the cylinder are mounted spiders 2^d to the peripheries of which are connected longitudinally disposed angle bars 3^a which are set so that one angle is flat and the other angle projects radially of the shaft, the said bars however lying longitudinally parallel with the shaft. These bars and spiders constitute a rotary carrier or conveyer within the cylinder by which the cans or packages are moved around in the cylinder as hereinafter explained; and within the cylinder 1 and secured to the internal wall thereof is a spiral guide rib 4 which extends from the feed to the delivery end of the cylinder.

The feed inlet is provided with a spout 1^d which projects from the side of the cylinder and is adapted to receive cans and direct them into the cylinder slightly above the level of the shaft and at the wide end of the spiral 4.

The cans enter between the adjacent bars 3^a on the cylinder, and are carried around with said bars as the cylinder rotates and the spiral guide 4 causes the cans to slide endwise of the cylinder until eventually the can reaches the head 1^b of the cylinder where it comes over an annular flange 4^a on said head, which flange is of slightly less diameter than the spiders 2^d so that the adjacent ends of the bars 3^a can project from this flange 4^a as shown, and the adjacent ends of the bars 3^a have their inner web portions notched or cut away as at 3^c, adjacent flange 4^a, so that the cans will pass onto and roll upon this flange 4^a when they reach the end of the cylinder adjacent head 1^b. This flange 4^a is provided with a discharge slot 4^b which communicates with a discharge spout 4^c extending out of the head so that cans are discharged by gravity at this point.

The spout 4^c is provided with a steam pipe 100

4^a by which any steam that may pass out with the can may be directed out of the building, and similarly feed spout 1^a may be provided with a pipe 1^b by which any 5 waste steam may be directed out of the building.

In order to cook the contents of the cans thoroughly we preferably subject the cans to the action of steam jets as they move with 10 and along the carrier. For this purpose, an annular pipe or header 5 may be attached to the spider 2^a adjacent the head 1^a, and to this annular head or ring 5 are connected perforated pipes 5^b which extend parallel 15 with and beside the flanged bars 3^a in such position that when a can is lying between any two bars 3^a it will be subjected to the action of steam issuing through the adjacent parallel pipe 5^b. In this way steam 20 may be applied to each and every can on the carrier during the time that it is traveling within the cooking chamber.

The header 5 may be connected by a radially disposed pipe 5^a to a pipe 5^c which 25 extends out of the closed end of the pipe 2 and is connected by a suitable rotary stuffing box 2^a with pipe 2^b which may be led to any suitable source of steam supply.

Steam may also be supplied to the interior of the cooker, if desired, by making 30 shaft 2 hollow, as shown, and providing it with perforations 2^c; and steam may be supplied to this hollow shaft through perforations 2^c which communicate with an annular chamber 1^c in the journal bearing 1^c of shaft 2 on head 1^a. This chamber 1^c is connected by a pipe 7 to any suitable steam supply, not shown, and when steam is admitted through this pipe into chamber 1^c it 35 will pass through perforations 2^c into shaft 2 and then escape through perforations 2^c into the interior of the cylinder.

If desired the water of condensation can 40 be removed from the chamber through a suitable cock 8 located at any desired level; or it may be entirely removed through a suitable drain pipe 8^a connected with the bottom of the chamber.

In case it is desired to use both steam and 45 water in heating the cans, the water may be heated by means of steam introduced into the bottom of the chamber through pipes 7^b connected to a pipe 7^a that is connected to pipe 7. All these steam supply and drain 55 pipes may be suitably valved, as is well understood.

The carrier may be operated by any desired means. As shown a pinion 6 is secured on the outer end of the shaft 2 and 60 meshes with a worm gear 6^a on a transverse shaft 6^b journaled in brackets attached to the head 1^a, and on this shaft 6^b is a pinion 6^c meshing with a pinion 6^d on a stub shaft 6^e attached to a bracket 6^f and carrying a

driving pulley 6^h, which can be belted to any suitable source of power. The worm 6^c is preferably made loose on shaft 6^b and may be locked thereto by means of a clutch 6^g of any suitable type, and operated by clutch levers in the usual manner.

To change the speed, for slow or fast cooking, different sized pulleys 6^h are employed, and such pulley may be placed on the spindle 6^e, and after the spindle is set to tighten the belt it may be locked in place; 75 such drive adjusting means are well known and are not claimed herein. The rear head may be provided with a man-hole for cleaning out, and a drain or blow off 8^a is provided at the bottom.

In the construction shown steam is preferably admitted through pipe 5^c to the header 5 and is distributed to the jet pipes 5^b and directed onto the cans resting upon the bars 3^a. Steam may also be admitted, 85 if desired, through the pipe 7 and central perforated shaft 2. Steam is used at low pressure and any superfluous steam that passes out at the inlet or exhaust spouts is conducted off through pipes 1^b and 4^a, which 90 pipes can be extended out of the building.

The shaft 2 is rotated preferably continually, or step by step as desired, to cause the carrier to rotate and the cans to move around with the carrier; and as the cans 95 rotate the spiral 4 causes them to slide endwise on the bars, and travel from the feed to the discharge end of the chamber in the desired length of time.

Operation: The machine is especially designed for cooking fruit after it is sealed up in the cans by means of steam or hot water.

If it is desired to use water for heating the cans the machine is filled about half full of water, or until the water covers the shaft 105 2. Steam is then admitted through the pipes 2 and 7^b and heats the water; if superheated the temperature in the tank can be raised to about 216 degrees without pressure. The cans when placed in the feed 110 spout roll into the troughs or grooves formed between adjacent bars 3^a as they successively pass the spout 1^a; and as the cans come into contact with the spiral guide 115 4 they are forced along endwise of the carrier, as it revolves toward the discharge, finally passing onto the flange 4^a and dropping out through the spout 4^a. When using water the cans will be in the water about one-half of the time, and one-half of the 120 time out of the water. The cans are preferably heated by steam issuing from the jet pipes 5^b while they are being moved. When the cans are out of the water they are cooked by steam; when the cans enter the water, 125 the steam escaping from the jet pipes heats the water around the cans. If it is desired to cook entirely by steam no water is used.

Steam is simply admitted through the jet pipes 5^b, the steam spraying on the cans as they revolve.

This machine is particularly designed for 5 cooking by what is called the open process, and fruit requiring about 212 degrees of heat; and not designed for cooking anything that requires steam pressure. By having a steam jet pipe near each row of cans on the 10 carrier and blowing steam directly onto the cans we can easily obtain a temperature from 212 degrees to 216 degrees F., and this lessens the time ordinarily required for cooking.

15 What we claim is:

1. In combination, a cooking chamber, a rotatable can carrier or conveyer therein, and steam jet pipes attached to the conveyer and moving therewith to direct jets 20 of steam onto the cans being moved by the conveyer.

2. In combination, a cooker, a cylindric chamber having an interior spiral can guide extending from the feed to the discharge end 25 thereof, a rotatable carrier in said chamber adapted to receive the cans and compel them to turn with the carrier while the spiral compels the cans to move lengthwise of the carrier, and jet pipes moving with the carrier adapted to direct jets of steam upon the cans, substantially as described.

3. In combination, a cooker, a cylindric chamber having an interior spiral guideway extending from the feed to the discharge 35 end thereof, a rotatable carrier in said chamber provided with longitudinal grooves to receive the cans and compel them to turn with the carrier while the spiral compels the cans to move lengthwise thereof and longitudinally disposed jet pipes extending beside the grooves and adapted to direct jets 40 of steam upon the cans therein, and means for supplying steam to such jet pipes.

4. In combination, a cylinder having opposite heads, a spiral guide therein, a can carrier within the cylinder comprising a shaft, and parallel flanged bars mounted on said shaft, a feed inlet, a discharge outlet at one end of the cylinder, an annular 50 flange attached to the cylinder adjacent the discharge and projecting under the adjacent ends of the flanged bars and adapted to support the cans that reach that end of the cylinder until they drop into the discharge.

5. In combination, a cylindric cooking chamber; a carrier therein comprising a shaft, spiders thereon, and parallel flanged bars supported on said shaft; with steam jet pipes arranged intermediate the said bars, a header connected with said pipes, and a steam supply connected with said header.

6. In combination, a chamber, a can carrier within the chamber, a discharge outlet at one end of the chamber, an annular flange

adjacent the discharge outlet and projecting 65 into the adjacent end of the carrier and adapted to support the cans that reach that end of the chamber until they drop into the discharge.

7. In combination, a cylindric cooking 70 chamber, a carrier therein comprising a shaft, parallel flanged bars supported on said shaft; steam jet pipes arranged intermediate the bars, and a header connected with one end of said pipes and a steam inlet 75 pipe connected with said header; with means for regulating the depth of water in the chamber, a feed inlet and a discharge outlet, and means for causing the cans to move longitudinally on the carrier as the latter 80 is rotated substantially as described.

8. In combination with a cylindric chamber having a feed inlet and a discharge outlet, a carrier in said chamber comprising a hollow shaft, spiders mounted on said shaft, 85 bars mounted on said spiders; means for admitting steam into said hollow shaft; and means for regulating the depth of water in the chamber; with an annular flange in the chamber adjacent the discharge outlet 90 adapted to support cans reaching that end of the chamber, and a spiral within the chamber and surrounding said carrier adapted to cause the cans to move longitudinally 95 on the carrier, as the latter rotates, until they reach the discharge.

9. In a can cooking machine, the combination of a chamber, a spiral can guide therein, a rotatable carrier within said chamber and guide having longitudinally disposed 100 channels adapted to receive cans and compel them to move around with the carrier while the spiral compels the cans to move longitudinally in the channels, a can inlet, a can discharge extending into the chamber 105 adjacent one end of the guide, and a circular flange member adjacent the said discharge and projecting into the end of the carrier so as to direct cans reaching such end into said discharge. 110

10. In a can cooking machine, the combination of a chamber, a spiral can guide therein, a rotatable carrier within said chamber having longitudinally disposed flanged bars adapted to compel cans to turn around with 115 the carrier while the spiral compels the cans to move longitudinally of the carrier, a can inlet at one end of the chamber, a can discharge at the other end of the chamber extending into the adjacent end of the said 120 carrier, and a stationary flange adjacent the said discharge opening and projecting into the end of said carrier and adapted to direct cans around said flange to said discharge.

11. In combination, a cylinder; a carrier 125 therein comprising a shaft, spiders mounted on said shaft, and bars mounted on said spiders; a feed inlet and a discharge out-

4
let, an annular flange adjacent the discharge outlet and projecting into the adjacent end of the carrier, and a spiral within the cylinder and surrounding said carrier adapted to cause the cans to move longitudinally on the carrier as the latter rotates until the cans reach the flange and enter the discharge, substantially as described.

In testimony that we claim the foregoing as our own, we affix our signatures in presence of two witnesses.
